ELECTRICAL CONDENSER

Carther M. Jorgensen, Chicago, Ill., assignor to
 Underwood Electric & Mfg. Co., Inc., Chicago,
 Ill., a corporation of Illinois

Application January 6, 1941, Serial No. 373,235

9 Claims. (Cl. 175—41.5)

The present invention relates to electrical condensers, and is particularly concerned with adjustable electrical condensers of the type which have a relatively small range of adjustment, and which are usually adjusted to predetermined capacity at the factory. Such electrical condensers have been called "padders" in the trade.

One of the objects of the invention is the provision of improved electrical condensers of the type having a limited range of adjustability, which are primarily intended to be set at the factory at desired capacities.

Another object of the invention is the provision of electrical condensers of the class described, which have a high degree of mechanical stability, and which are adapted to maintain their capacity at the predetermined value for a long period of time, with a minimum amount of drift.

Another object of the invention is the provision of an improved condenser structure in which the mica plates are protected and aligned and their rotation is prevented by the structure of the clamping plates, and in which improved means is provided for mounting the condensers on the chassis without a bracket.

Another object of the invention is the provision of an improved condenser structure which provides better control of stability, and in which the condenser may be provided with any lengths of soldered leads, or constructed with any number of insulated plates.

The riveted connectors of the prior art, which have been used with condensers, tend to oxidize, which changes their capacity and renders the oxidized plate inoperative.

Another object of the invention is the provision of an improved condenser structure which is simple, efficient, capable of economical manufacture, and which is peculiarly adapted to be utilized as the by-pass condenser for the aerial of a radio receiving set having a direct connection which reduces the inductance and increases the capacitor's effectiveness.

Another object of the invention is the provision of an improved condenser structure by means of which a multiplicity of condensers may be placed in one assembly for the purpose of producing results equivalent to a series of condensers used in some electrical circuits, thereby reducing effective inductance introduced in the circuits by the necessity of connecting several condensers into the assembly.

Other objects and advantages of the invention will be apparent from the following description and the accompanying drawings, wherein similar characters of reference indicate similar parts throughout the several views.

Referring to the drawings, of which there are two sheets,

Fig. 1 is an enlarged bottom plan view of a condenser constructed according to the invention, mounted on a portion of the chassis;

Fig. 2 is a top plan view of the chassis, with parts of the condenser exposed for access;

Fig. 3 is a vertical sectional view, taken on the plane of the line 3—3 of Fig. 1, looking in the direction of the arrows;

Fig. 4 is a horizontal sectional view, taken on the plane of the line 4—4 of Fig. 3;

Fig. 5 is a fragmentary sectional view, taken on the plane of the line 5—5 of Fig. 2;

Fig. 6 is a bottom plan view of another modified form of structure, which is provided with a plurality of condensers in one assembly;

Fig. 7 is a side elevational view of the assembly of Fig. 6;

Fig. 8 is a view similar to Fig. 6 of another modification, which is provided with a bracket for the mounting of the condenser on a supporting bar or the like;

Fig. 9 is a side elevational view of the assembly of Fig. 8; and

Fig. 10 is a plan view of a condenser embodying the invention, secured to the aerial jack of a radio receiver for the purpose of providing a more direct connection to reduce inductance and increase capacitor's effectiveness.

Fig. 11 is a side elevational view of the structure of Fig. 10;

Fig. 12 is a sectional view, taken on the plane of the line 12—12 of Fig. 11;

Fig. 13 is a side elevational view of another modification of the type shown in Fig. 4, which is provided with an improved form of supporting bracket;

Fig. 14 is a plan view of one of the condenser plates;

Fig. 15 is a plan view of one of the sheets of mica;

Fig. 16 is a fragmentary sectional view, taken on the plane of the line 16—16 of Fig. 2.

It should be understood that the condensers may be mounted above or below the chassis, but for the purpose of this description that side of the condenser having the head of the adjusting screw exposed has been termed the top.

Referring to Figs. 1 to 3, 20 in this embodiment indicates a sheet metal plate which forms a part of the supporting structure of the chassis. It is preferably provided with a pair of relatively long rectangular slots 21, 22 oppositely located with respect to an enlarged centrally located circular aperture 23.

The slots 21 and 22 are so located that when the head 24 of the condenser screw bolt 25 is accessible and centrally located in the aperture 23, the lugs 26 and 27 of the condenser assembly

register with the apertures 21, 22, through which they are passed.

The plate 20 is also preferably provided with a pair of oppositely located circular apertures 28, 29 for receiving the lugs 30, 31 carried by side walls of the condenser.

The condensers constructed according to the invention preferably comprise the two clamping plates 32, 33, and the clamping plate 32 may be octagonal in form and provided with four spaced side wall flanges 34 to 37.

The side wall flanges 34 to 37 extend at right angles to the body of the plate 32, and are located on alternate sides of the octagon which forms the border of the plate. This leaves open spaces in the side wall between each of the flanges 34, 35; 35, 36; 36, 37; 37, 34, through which the connector strips of the condenser plates may project with a clearance.

The side wall flanges 34-37 may be provided with straight flat ends as in the embodiment of Figs. 6 and 7; but in the embodiment of Figs. 1 to 4 these side wall flanges carry the additional lugs which are used to attach the condenser to the chassis plate 20. Thus the side wall flanges 34 and 36 may carry the lugs 30 and 31, which project into the apertures 28 and 29 of the chassis plate 20 and prevent rotation of the condenser on the plate 20.

The side wall flanges 35 and 37 may carry the lugs 26 and 27, which are of greater width, being of a size adapted to pass through the apertures 21 and 22, with which they register when the lugs 30 and 31 are in the apertures 28 and 29. The lugs 26 and 27 are formed with laterally and inwardly extending slots 38. These slots have their side wall, which is nearest to the end of the lug 26 or 27 so located that it will engage the face of the plate 20 when the condenser has the ends of the flanges 34-37 engaging the other side of the plate.

Thus the lugs 26, 27 may be inserted through the apertures 21, 22, and the portions 39, 40 of these lugs may be bent laterally to retain the condenser on the plate. It is the presence of the slots 38 which renders it desirable to provide the lugs 30 and 31 for preventing rotation.

The slots 38 preferably slope downward and from the edge of each lug, shown in Fig. 16, so that the sloping surface 41 on each lug 39 or 40 serves to cam the condenser tightly against the plate 20.

The plate 32 is provided with a centrally located aperture 42, which is threaded to receive the shank of the screw bolt 25.

The other plate 33 comprises an octagonal metal plate of sufficient size so that its sides fit inside the side walls 34-37 of the plate 32. It is preferably provided with a centrally located aperture 43 for passing the shank of the screw bolt 25 and a pair of intersecting slots 44, 45 communicating with the aperture 43.

The slots 44, 45 might also be described as a plurality of radially extending slots, preferably equally spaced. In the embodiment illustrated they are at right angles to each other. These slots 44, 45 serve to give that portion 46 of the plate 33, which is between them, a greater resiliency, so that the plate may be slightly dished outwardly from the condenser assembly at the parts 46.

If it were not for the slots 44, 45, the dished formation in the plate 43 would necessarily be very stiff and the plate would not clamp the

condenser plates and mica sheets with the same resiliency as the present structure.

Referring to Fig. 14, this is a plan view of a thin brass condenser plate 47 utilized in the condenser assembly. It has a hexagonal body 48 of slightly smaller size than the plate 33, and of course it is smaller than the inside of the housing which is formed by the plate 32 and flanges 34-37, so that there will be a clearance between the condenser plates and the housing.

The condenser plates all have an enlarged centrally located aperture 49, which passes the screw bolt with a relatively large clearance to prevent contact between the condenser plates and the adjusting screw bolt.

The body 48 of each condenser plate has a laterally projecting flange or tab 50, which projects laterally from one of the flat sides and serves as a connector. It also serves the purpose of holding the plates in alignment in a jig while the condenser is being assembled.

The tab 50 may be described as substantially rectangular in plan. It is provided with a pair of inwardly extending and oppositely located rectangular slots 51, 52. These serve to receive a clip which holds the connecting wire to the condenser, and which holds the tabs in alignment.

The tab or flange 50 also has a centrally located aperture 53, which is adapted to receive the laterally turned end 54 of a connecting wire or loop 55, which serves to secure together one or more different plates, forming a strong mechanical connection preliminary to soldering.

Referring to Fig. 15, this is a plan view of one of the mica plates. It is also octagonal in form, being provided with the sides 56 of greater length and the sides 57 of smaller length. This gives the mica plates such a shape that the portions bounded by the sides 57 project slightly, as shown at 58, from the housing between the side walls 34-37, increasing the width of these insulating plates at the point where the terminals 50 project from the housing.

The condenser may be built up of any number of metal plates and dielectric plates, the mica plates being interposed between the metal plates.

The preferred practice is to have the outermost brass plates bearing against the heavy clamping plates 32, 33 above and below so that the heavy plates, that is, the housing 32 and the pressure plate 33, are common to one side of the condenser.

In other embodiments, however, a heavy mica plate may be inserted between the brass plate and the housing, above and below, so that the housing is also insulated from all of the brass plates.

The method of assembling the condenser is as follows: The housing 32 is first placed upon a suitable jig or support, the jig being provided with shoulders for locating the housing, and with upwardly extending lugs suitably located with respect to the housing and adapted to be received within the slots 51 and 52 of the brass plates, to be assembled with the housing. Two lugs may be provided on each of the four open sides of the housing, so that when it is desired to have the tabs 50 project from all four sides, as shown in Fig. 6, this can be done.

Referring to a simple embodiment, such as Figs. 1 to 3, the brass plates and mica plates are then alternately placed inside the housing 32. The mica plates are maintained in proper align-

ment with their centrally located aperture aligned with the screw aperture 42 by the side walls 34-37 which the edges of the mica sheets engage.

The brass plates are maintained in proper alignment inside the housing by the lugs of the jig, which fit in the slots 51, 52 of the tabs 50. After a suitable number of mica sheets and brass plates have been placed in the housing, the pressure plate 38 is placed on top and the screw 25 inserted into the threaded bore 42 and driven home to clamp the brass plates and mica plates together by means of the pressure plate 38.

The condenser may then be removed from the jig and completed by inserting the wires 55 with their laterally turned ends 54 extending through the registering apertures 53. With the wire in this position a sheet metal clip 59 is bent about the wire 55, and tabs 50, the clip being of sufficient width to fit inside the aligned slots 51, 52 of the assembly of brass plates, and the clip has its upper side bent to substantially cylindrical shape at 60 to fit about the wire.

Below the assembly of connector flanges 58 the clip 59 has its ends bent over toward each other at 61 so that the wire is clamped in place with its end projecting through the apertures 53.

The clip and the wire are then covered with solder on the upper and lower sides so that the clip is soldered to the wire and to the condenser flanges 58, and the various condenser flanges are also soldered together, leaving the wire 55 projecting radially from the condenser. By this form of connecting wire a connector is assured which will never deteriorate due to oxidation, and of course the wires may be provided of any convenient length for the purchaser so that it is not necessary to utilize other wires to connect these condensers in circuit.

Therefore, a considerable saving may be effected and a more efficient condenser provided by means of this connection than any other. Before the condenser leaves the factory, its adjustment screw 25 is so adjusted that the condenser has the desired predetermined capacity. The various mica sheets and plates are held in proper position and clearance with respect to the screw by the frictional engagement between these sheets under the clamping action of the plate 38 and housing 32. They are also held in predetermined position with respect to each other by the fact that all of the condenser plates which have a flange projecting from one side are secured together at that flange by soldering and by means of the wire and clip in such manner that the plates cannot get out of alignment.

The condenser plates have a relatively large clearance around the screw, due to the size of the aperture 49, but the mica plates have a smaller aperture so that they project inwardly beyond the border of the aperture 49 of each condenser plate. The mica aperture is, however, preferably slightly larger than the threads of the screw, so that the threads will not tear the mica.

Referring to Figs. 6 and 7, these are views of a modification in which condenser plates insulated from each other have connector flanges extending from all of the four sides of the assembly, and in fact two condenser plate assemblies at the left of the figure are provided with two separate wires 62, 63. Thus, a multiplicity of condensers, insulated from each other, but in electrostatic relation with respect to each other, may be secured in the same assembly.

There are various forms of filter and resonant

circuits which these condenser assemblies serve to replace at a minimum cost, and with a high degree of efficiency.

Referring to Figs. 8 and 9, these are views of a modified form of condenser which is provided with an attaching bracket 65 for attachment to the bars or plates of a supporting chassis. In this embodiment the bracket 65 comprises a plate having a rectangular body and having the upwardly extending rectangular tabs 66. The body of the plate is soldered, brazed, or otherwise secured to the housing, and has a centrally located aperture for passing the screw bolt 25.

The plate to which this bracket is secured is indicated at 68, and it comprises a strap of metal which has an aperture 67 for clearance with respect to each of the screws of the condensers that are attached to it. It is attached by bending the flanges 68 over and about the strap 68 in such manner as to secure the condenser to the supporting member 68.

Referring to Fig. 13, in this embodiment the housing of the condenser has an angular bracket 70, comprising a strap of metal which is bent at right angles at 71, and which has one portion again provided with an aperture 72 for clearance about the screw bolt 25.

The end portion 73 is soldered or otherwise secured to the housing 32, and the upwardly extending leg 74 of the bracket has an aperture 75 for passage of a screw bolt 76.

The protuberance 77 is formed in the leg 74 by a pressing operation, which also forms a depression 78. The protuberance 77 is received in a complementary aperture 79 in the supporting plate 68 of the chassis.

Referring to Figs. 10-12, this is a modification in which the side walls 34-37 of the housing have been eliminated and the two heavy plates 85, 86 serve as condenser plates. The heavy plate 85 is similar in structure to the housing 32 in that it is provided with a threaded aperture for receiving the threaded end of the screw bolt 87.

It also has an offset narrower flange 88, which carries a partially cylindrical flange 89 that fits about the outside of a jack 90, such as may be used for connection to an aerial in the radio receiver of an automobile.

The single condenser plate 81 may be circular, and may have an enlarged centrally located aperture 49, as described in Fig. 14, and a downwardly extending connector tab 92 which extends between the two flanges 88 of the connector of the jack.

The flanges 88 have an aperture 94 so that a wire extending through these apertures may also engage the connector tab 92 of the condenser. The pressure plate 38 is circular and provided with slots 44, 45, as shown in Fig. 4; and mica sheets are, of course, interposed between the condenser plate 81 and each of the plates 85, 86.

This condenser provides such a short and direct connection between its elements and the jack connectors that the leads of this condenser have a minimum amount of inductance, and the condenser assembly is very effective as a by-pass condenser for the jack of an aerial of an automobile radio receiving set.

The difficulty with most condensers for this purpose is that the leads are too long, and for high frequency currents such long leads would increase the inductance of the by-pass circuit by such an amount that the capacity of the condenser would be cancelled out and substantially ineffective.

In the present embodiment, however, the bypass condenser has maximum effective capacity, due to a minimum amount of inductance.

It will thus be observed that I have provided an improved electrical condenser structure which may be manufactured very economically, and which is adapted to give a better control of stability.

My condensers may be used with a multiplicity of leads, and a multiplicity of condensers may be provided in one assembly. There is no possibility of the plates becoming inoperative due to oxidation of a riveted connection, since all of the plates are soldered together and soldered to a connector wire, which is also a very convenient and economical mode of connecting the device in circuit. As a mechanical joint is provided first, and the plates are then sweated together with solder, the wire is firmly and permanently secured to the condenser plates, and the assembly may be furnished with any reasonable length of wire desired. This renders the present condenser assemblies more salable than the devices of the prior art in which a long soldered lug or wire is riveted to the condenser plates.

The present condensers are provided with various convenient structures for securing them to the chassis, and with means for indexing and preventing rotation of the condensers on the chassis. While these condensers are best adapted for capacities of, for example, from 300 to 6,000 microfarads, they can also be built to high capacities and to lower capacities. The assemblies in which a multiplicity of condensers are embodied in one structure are adapted to replace various types of filters and other circuits utilizing condensers, and to perform the same function efficiently, at a very low cost.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In an electrical condenser, the combination of a housing of substantially octagonal form, said housing having four open sides and four sides closed by upwardly projecting flanges, a plurality of condenser plates and mica insulating plates alternately disposed and located in said housing, a pressure plate above the assembly of said condenser plates and mica plates, a screw bolt passing through said pressure plate and threaded into said housing plate, said condenser plates having laterally projecting connector flanges extending through the open sides of said housing and adapted to be used for connecting the plates in circuit.

2. In an electrical condenser, the combination of a housing of substantially octagonal form, said housing having four open sides and four sides closed by upwardly projecting flanges, a plurality of condenser plates and mica insulating plates alternately disposed and located in said housing, a pressure plate above the assembly of said condenser plates and mica plates, a screw bolt passing through said pressure plate and threaded into said housing plate, said condenser plates having laterally projecting connector flanges extending through the open sides of said housing and adapted to be used for connecting the plates

in circuit, said pressure plate having a dished formation adjacent its aperture and having radially extending slots for increasing the resiliency of the dished formation.

3. In an electrical condenser, the combination of a housing of substantially octagonal form, said housing having four open sides and four sides closed by upwardly projecting flanges, a plurality of condenser plates and mica insulating plates alternately disposed and located in said housing, a pressure plate above the assembly of said condenser plates and mica plates, a screw bolt passing through said pressure plate and threaded into said housing plate, said condenser plates having laterally projecting connector flanges extending through the open sides of said housing and adapted to be used for connecting the plates in circuit, said mica plates fitting substantially in said housing, and said condenser plates having a clearance with respect to said housing and being maintained in predetermined position by frictional engagement with the rest of the assembly under the clamping action of said screw bolt.

4. In an electrical condenser, the combination of a housing of substantially octagonal form, said housing having four open sides and four sides closed by upwardly projecting flanges, a plurality of condenser plates and mica insulating plates alternately disposed and located in said housing, a pressure plate above the assembly of said condenser plates and mica plates, a screw bolt passing through said pressure plate and threaded into said housing plate, said condenser plates having laterally projecting connector flanges extending through the open sides of said housing and adapted to be used for connecting the plates in circuit, said connector flanges which extend in the same direction being secured together by a mechanical connection and a soldered connection.

5. In an electrical condenser the combination of an external housing plate having a plurality of transversely extending guide flanges separated from each other by slots, said plate having a centrally located threaded aperture, a plurality of metal condenser plates and a plurality of insulating sheets arranged alternately in a stack to insulate said condenser plates from each other and from said housing plate, said insulating sheets being shaped to engage said guide flanges, and a pressure plate engaging the assembly of insulating plates and condenser plates, said pressure plate having a centrally located aperture surrounded by a dished portion and having radially extending slots extending from said aperture in said dished portion, and a threaded metal member extending through said pressure plate and threaded into said housing plate to place a predetermined compression upon the assembly of the insulating plates and condenser plates, said condenser plates being formed with integral radially extending connector portions and said condenser plates being arranged in at least two series of plates, the plates of each series being insulated from the plates of the other series and the plates of different series having their connector portions extending through different slots in said housing, and means for securing said connector portions together to assure the location of said condenser plates in said assembly with the condenser plates out of contact with the threaded member and the housing flanges.

6. In an electrical condenser the combination of an external housing plate having a plurality

of transversely extending guide flanges separated from each other by slots, said plate having a centrally located threaded aperture, a plurality of metal condenser plates and a plurality of insulating sheets arranged alternatively in a stack to insulate said condenser plates from each other and from said housing plate, said insulating sheets being shaped to engage said guide flanges, and a pressure plate engaging the assembly of insulating plates and condenser plates, said pressure plate having a centrally located aperture surrounded by a dished portion and having radially extending slots extending from said aperture in said dished portion, and a threaded metal member extending through said pressure plate and threaded into said housing plate to place a predetermined compression upon the assembly of the insulating plates and condenser plates, said condenser plates being formed with integral radially extending connector portions and said condenser plates being arranged in at least two series of plates, the plates of each series being insulated from the plates of the other series and the plates of different series having their connector portions extending through different slots in said housing, and means for securing said connector portions together to assure the location of said condenser plates in said assembly with the condenser plates out of contact with the threaded member and the housing flanges, said condenser plates having their connector portions formed with through apertures and said through apertures being placed in registry and engaged by the end of a through connector wire.

7. In an electrical condenser the combination of an external housing plate having a plurality of transversely extending guide flanges separated from each other by slots, said plate having a centrally located threaded aperture, a plurality of metal condenser plates and a plurality of insulating sheets arranged alternatively in a stack to insulate said condenser plates from each other and from said housing plate, said insulating sheets being shaped to engage said guide flanges, and a pressure plate engaging the assembly of insulating plates and condenser plates, said pressure plate having a centrally located aperture surrounded by a dished portion and having radially extending slots extending from said aperture in said dished portion, and a threaded metal member extending through said pressure plate and threaded into said housing plate to place a predetermined compression upon the assembly of the insulating plates and condenser plates, said condenser plates being formed with integral radially extending connector portions and said condenser plates being arranged in at least two series of plates, the plates of each series being insulated from the plates of the other series and the plates of different series having their connector portions extending through different slots in said housing, and means for securing said connector portions together to assure the location of said condenser plates in said assembly with the condenser plates out of contact with the threaded member and the housing flanges, said latter means comprising a metal clip secured about said connector portions and engaged in lateral slots of said connector portions.

8. In an electrical condenser the combination of an external housing plate having a plurality of transversely extending guide flanges separated from each other by slots, said plate having a centrally located threaded aperture, a plurality of

metal condenser plates and a plurality of insulating sheets arranged alternately in a stack to insulate said condenser plates from each other and from said housing plate, said insulating sheets being shaped to engage said guide flanges, and a pressure plate engaging the assembly of insulating plates and condenser plates, said pressure plate having a centrally located aperture surrounded by a dished portion and having radially extending slots extending from said aperture in said dished portion, and a threaded metal member extending through said pressure plate and threaded into said housing plate to place a predetermined compression upon the assembly of the insulating plates and condenser plates, said condenser plates being formed with integral radially extending connector portions and said condenser plates being arranged in at least two series of plates, the plates of each series being insulated from the plates of the other series and the plates of different series having their connector portions extending through different slots in said housing, and means for securing said connector portions together to assure the location of said condenser plates in said assembly with the condenser plates out of contact with the threaded member and the housing flanges, said latter means comprising a metal clip secured about said connector portions and engaged in lateral slots of said connector portions, and said metal clip and connector portions being soldered together.

9. In an electrical condenser the combination of an external housing plate having a plurality of transversely extending guide flanges separated from each other by slots, said plate having a centrally located threaded aperture, a plurality of metal condenser plates, and a plurality of insulating sheets arranged alternatively in a stack to insulate said condenser plates from each other and from said housing plate, said insulating sheets being shaped to engage said guide flanges, and a pressure plate engaging the assembly of insulating plates and condenser plates, said pressure plate having a centrally located aperture surrounded by a dished portion and having radially extending slots extending from said aperture in said dished portion, and a threaded metal member extending through said pressure plate and threaded into said housing plate to place a predetermined compression upon the assembly of the insulating plates and condenser plates, said condenser plates being formed with integral radially extending connector portions and said condenser plates being arranged in at least two series of plates, the plates of each series being insulated from the plates of the other series and the plates of different series having their connector portions extending through different slots in said housing, and means for securing said connector portions together to assure the location of said condenser plates in said assembly with the condenser plates out of contact with the threaded member and the housing flanges, said latter means comprising a metal clip secured about said connector portions and engaged in lateral slots of said connector portions, and said metal clip and connector portions being soldered together.

CARTHER M. JORGENSEN.
